(57) **CLAIM**

The ornamental design for a water cup, as shown and described.

DESCRIPTION

FIG. 1 is a front view of a water cup showing the new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view showing the front of water cup;

FIG. 8 is a perspective view showing the bottom of water cup;

FIG. 9 is a perspective view showing the top of water cup; and,

FIG. 10 is a perspective view showing the back of water cup. The broken lines in the drawings depict portions of the water cup that form no part of the claimed design.
